(57) **CLAIM**

The ornamental design for a Pulaski excavating attachment, as shown and described.

DESCRIPTION

FIG. 1 is a front perspective view of a Pulaski excavating attachment of the present disclosure;

FIG. 2 is a rear perspective view of the Pulaski excavating attachment shown in FIG. 1;

FIG. 3 is a right side elevational view of the Pulaski excavating attachment shown in FIG. 1;

FIG. 4 is a left side elevational view of the Pulaski excavating attachment shown in FIG. 1;

FIG. 5 is a rear elevational view of the Pulaski excavating attachment shown in FIG. 1;

FIG. 6 is a front elevational view of the Pulaski excavating attachment shown in FIG. 1;

FIG. 7 is a top plan view of the Pulaski excavating attachment shown in FIG. 1;

FIG. 8 is a bottom plan view of the Pulaski excavating attachment shown in FIG. 1; and,

FIG. 9 is a cross-sectional view taken along line 9-9 in FIG. 7. The broken lines in the drawings illustrate portions of the Pulaski excavating attachment and form no part of the claimed design.
